UNITED STATES PATENT OFFICE.

JOHN BEATHAM, OF RIO VISTA, CALIFORNIA.

LIQUID-FUEL BURNER.

Application filed August 27, 1923. Serial No. 659,620.

To all whom it may concern:

Be it known that I, JOHN BEATHAM, a citizen of the United States, residing at Rio Vista, in the county of Solano and State 5 of California, have invented certain new and useful Improvements in Liquid-Fuel Burners, of which the following is a specification, reference being had to the accompanying drawings.

10 This invention relates to liquid fuel burners.

An important object of the invention is to provide a simple and inexpensive fuel burner of this character having means whereby the 15 liquid fuel is converted to a gaseous one prior to the burning thereof.

A further object of the invention is to provide a device of this character composed of unitary castings, with the exception of 20 such necessary accessories as feed pipes and the like.

A still further object of the invention is to provide a device of this character which will operate evenly when the flow of fuel thereto 25 is comparatively low.

These and other objects I attain by the construction shown in the accompanying drawings, wherein for the purpose of illustration I have shown a preferred embodiment 30 of my invention and wherein:—

Figure 1 is a perspective view of the burner constructed in accordance with my invention;

35 Figure 2 is a side elevation partially in section thereof;

Figure 3 is a section on the line 3—3 of Figure 2; and

Figure 4 is a detailed sectional view showing the air inlet.

40 Referring now more particularly to the drawings, the numeral 10 indicates a unitary casting formed to provide a substantially cylindrical casing 11, the ends of which are closed by end plates 12 serving as a support for the burner. The casing 11 is subdivided to form main and auxiliary compartments 13 and 14, the main compartment comprising the body or gas chamber of the burner and the auxiliary compartment 45 being formed in the peripheral wall of the main compartment and being partially within and partially without the main compartment. The auxiliary compartment is provided adjacent one end wall 12 with an opening 15 communicating with the atmosphere and is provided in its upper wall

with a plurality of spaced openings 16, placing the compartments 13 and 14 in communication between the edges of the wall of the compartment 14 and points represented by 60 the intersection of a horizontal plane, designated at P, with the walls of the compartment 13, this plane passing through the approximate axis of the compartment 14. The walls of the compartment 13 are provided 65 with vertically extending longitudinally spaced slots 17. It will be noted that above the upper edges of the slots 17 a pocket is formed in the chamber 13, the purpose of which will presently appear.

The end walls or plates 12 are provided with aligned openings 18 through which extends a feed pipe 19, one end of which is adapted for connection with the supply pipe and the opposite end of which enters an 70 elbow 20 secured to the corresponding end plate and to the end wall in alignment with the end of the compartment 14, the end plate being that at the end of the casing 10 next adjacent the opening 15 of the compartment 75 14. The end of the supply pipe 18 is directed through an opening 21 formed in this end plate and into the compartment 14, terminating immediately above the opening 15 of the compartment.

80 In the operation of the device, assuming sufficient heat has been applied to the fuel pipe 18, to convert fuel passing therethrough into a gaseous vapor, this vapor discharging from the end of the supply pipe is mixed 85 with air entering at the opening 15. Being heated, the gas thus formed passes upwardly through the openings 16 of the wall of the compartment 14 and into the compartment 13, where still rising it collects in the pocket 90 above the upper ends of the slots 17. If the burner be horizontally positioned, as intended, this gas will escape from these pockets through the upper ends of the openings to be burned, the amount of gas passing 95 through each of the openings being approximately equal and accordingly a uniform flame from each of the openings will result. If the fuel feed be increased the amount of gas passing through each opening will increase. 100 It will be noted that the fuel feed pipe 18 approximately parallels the side of the compartment 13 in alignment with these slots and this feed pipe will be accordingly subjected not only to the confined heat of a 105 fire box in which the feed pipe is arranged, but likewise to the flame passing from the 110

openings and the transmitted heat of the casing 11. In order to provide for initial heating of the feed pipe a drip tray 22 may be provided, arranged beneath the feed pipe 18 between the end plates 12 and supported from the feed pipe by means of clips 23. The end plates 12 at the ends of the chamber 13 are provided with openings 24 affording access to the chamber 13 for cleaning thereof, these openings providing a means for suspending a core for use in forming a chamber 13 and being during operation closed by removable plugs 25.

It will be obvious from the foregoing that a burner constructed in accordance with my invention may be very cheaply produced and at the same time will afford a structure providing a uniform flame and admitting of the use of liquid hydrocarbons as fuel. It will furthermore be obvious that the structure thereof is capable of some change and modification without materially departing from the spirit of my invention and I accordingly do not limit myself to such specific structure, except as hereinafter claimed.

I claim:—

In a hydrocarbon burner, a casing formed to provide substantially cylindrical main and auxiliary compartments, said auxiliary compartment being formed in the lower wall of the main compartment and being disposed partially within and partially without the main compartment, openings formed in the wall of the auxiliary compartment connecting the compartments, an opening in the auxiliary compartment adjacent one end thereof communicating with the air, and the end wall of the main compartment being provided with an opening affording access thereto, a removable closure for said opening, and vertical slots formed in the wall of said main compartment having their lower ends disposed immediately adjacent the wall of the auxiliary compartment and their upper ends spaced thereby to provide in the upper end of the main compartment a gas pocket.

In testimony whereof I hereunto affix my signature.

JOHN BEATHAM.
